UNITED STATES PATENT OFFICE.

FREDERICK C. MORTON, OF MINNEAPOLIS, MINNESOTA.

GLIDER.

Application filed July 6, 1923. Serial No. 649,950.

To all whom it may concern:

Be it known that I, FREDERICK C. MORTON, a citizen of the United States, residing at Minneapolis, in the county of Hennepin and State of Minnesota, have invented new and useful Improvements in Gliders, of which the following is a specification.

This invention relates to toys and more particularly to toys of the aerial type, an object of the invention being to provide a glider which may be easily projected into the air and will sail, to provide amusement for the child playing with it.

Another object of the invention is to provide a glider structure as specified which embodies in its main construction a straight substantially rigid foundation or supporting pole from which the various parts of the different types of gliders are supported and which pole has suitable projecting means attached thereto.

Another object of this invention is to provide a glider which may be utilized as a kite if so desired and also to provide a glider in which the transverse angles of the front and rear planes vary, the rear plane, preferably, being concavely curved transversely, so as to provide an air pocket or lift to the glider by the air rushing over the forward plane and pocketing under the rear plane.

Another object of this invention is to provide a novel type of glider in the form of a parachute carried by one end of the main supporting stick and collapsed therover when the glider is shot or projected into the air, which parachute opens out as the glider starts to fall, and supports the glider so as to materially retard its descent.

Other objects of the invention will appear in the following detailed description taken in connection with the accompanying drawings wherein:

Fig. 1 is a top plan of the improved glider.

Fig. 2 is a side elevation of the glider.

Fig. 3 is a vertical section on the line 3—3 of Fig. 1.

Fig. 4 is a vertical cross section on the line 4—4 of Fig. 1.

Fig. 5 is a top plan of a modified form of the glider.

Fig. 6 is a side elevation of the modified form of the glider.

Fig. 7 is a cross section on the line 7—7 of Fig. 5.

Fig. 8 is a side elevation of the parachute type of glider showing it in position to be projected into the air.

Fig. 9 is a side elevation of the parachute type of glider showing it in the position assumed during its falling.

Fig. 10 is a cross section on the line 10—10 of Fig. 8.

Fig. 11 is a plan view of the parachute illustrating, by dotted lines, the manner of folding the parachute to collapse it upon the end of the body stick.

Fig. 12 is a side elevation of a further modified form of the glider.

Fig. 13 is a section on the line 13—13 of Fig. 12.

Referring more particularly to the drawings, the improved glider comprises a body stick 1, which is preferably formed of wood and has suitable projecting means attached thereto intermediate its end. In the present invention, and in all of the forms illustrated in the drawings, a strip 2 of rubber is attached to the body stick 1 in any suitable manner preferably by windings of thread, string or the like as shown at 3 in Figs. 1 and 2 of the drawings so as to permit the projecting of the glider into the air.

In the preferred form of the invention shown in Figs. 1 to 4 inclusive the body stick 1 has front and rear plane frames attached thereto. The front plane frame 4, is formed of a single length of wire which has one end wound about the body stick as shown at 5 and bowed therefrom to the forward end of the stick where it is twisted about the stick as shown at 6 and returned along the opposite side of the body stick to its initial point of connection where it is again wound about the body stick as shown at 8 so as to provide the substantially oval shaped supporting frame 4 upon which the cloth plane 9 is mounted. As clearly shown in Figs. 2 and 3 of the drawings, the plane 9 is concavely curved presenting a concave surface upwardly and having its edges raised above the body stick 1 so as to permit proper engagement of the air to guide the stream of air deflected by the projection of the glider beneath the convexly curved rear plane 10. The rear plane 10 is formed of fabric or any suitable material and is mounted upon a frame 11 which is attached

to the body stick 1 in the same manner in which the frame 4 is attached.

A rudder or center board 12 of any suitable material, preferably paper may be attached to the under surface of the body stick beneath the rear plane 10 and it may be braced by suitable braces 13, if desired.

A tail 14 of the type commonly used on kites may be attached to the body stick 1 to permit the use of the glider as a kite.

In Figs. 5 to 7 of the drawings a modified form of the glider is shown. The modified form of glider comprises the body stick 1^a which has a projecting rubber 2^a attached thereto intermediate its ends by means of windings 3^a of thread, string or the like. The stick 1^a has a front plane 9^a mounted thereon and a rear plane 10^a. The planes 9^a and 10^a, are preferably formed of relatively stiff paper or other suitable material and they are attached to the body stick 1^a by any suitable type of adhesive. The planes 9^a and 10^a are preferably bent or folded to snugly embrace the stick 1^a, as shown at 4^a, and the forward plane 9^a is reinforced at its tip and tail ends by reinforcing strips 5^a and 6^a. The forward plane 9^a has its rear corners slightly downturned as shown at 7^a in Fig. 7 of the drawings. The rear plane 10^a is convexly curved, so as to properly engage the air and assist in supporting the glider during travel. A rudder 12^a may be attached to the body stick 1^a. A substantially triangular shaped tail tab 13^a is attached to the body stick 1^a and extends in flatwise manner rearwardly of the rear end of the plane 10^a providing a tip which may be gripped by the thumb and finger of the user during the projecting of the plane.

In Figs. 12 and 13 of the drawings, a further modification of the type of glider shown in Figs. 5, 6 and 7 of the drawings is provided. In Figs. 12 and 13 of the drawings the rudder 12^a is eliminated and an up-standing fin or rudder structure 12^b is provided which is preferably attached to the stick 1^b at the center of the stick and extends upwardly therefrom. The fin or rudder 12^b is formed of a piece of pasteboard or similar material and it is folded across the under surface of the stick 1^b and extends upwardly on each side of the stick, as clearly shown in Fig. 13 of the drawings. An insert 20^c is placed between the upper edges of the up-standing sides 21^c of the fin or rudder and is attached thereto by suitable clips 22^c. In Fig. 12 of the drawings the insert 20^c is shown in the shape of a man holding a steering wheel to simu-

late a pilot for driving the glider. The projector 2^c is attached to the stick 1^c between the sides 21^c.

In Figs. 8 to 11 of the drawings a further modified form of the glider is shown which is the parachute type. This form of glider comprises a body stick 1^b which has a projecting rubber 2^b attached thereto by windings 3^b of string or the like for projecting it into the air. The stick 1^b has a collar 4^b mounted on one end thereof against which collar the disc 5^b is adapted to engage to limit the outward movement of the parachute 6^b relative to the body stick. The disc 5^b is slidable on the body stick 1^b and is connected by means of a plurality of strings 8^b to the parachute 6^b. The parachute 6^b is formed of cloth or any suitable material and it is folded or creased along the lines indicated at 9^b so as to permit it to assume a collapsed conical shape and fit snugly over the end of the body stick 1^b during the projection of the glider. After the glider has been projected and when it starts to fall, the body stick being heavier and more susceptible to the gravity action than the parachute will fall faster upon its initial starting to fall which will cause the parachute 6^b to be extended about the upper end of the body stick 1^b so as to catch the air which will open out the parachute and retard the descent of the glider.

It is, of course, to be understood that the invention may be constructed in other manners and the parts associated in different relations and, therefore, I do not desire to be limited in any manner except as set forth in the claims hereunto appended.

Having thus described my invention what I claim is:

1. A glider comprising a body stick, means on the body stick for projecting it into the air, forward and rear planes carried by the body stick, said rear plane being convexly curved and presenting its convex surface upwardly, the forward plane being concavely curved and presenting a concave surface upwardly, and a rudder carried by the body stick.

2. A glider comprising a body stick, front and rear planes carried by the body stick, said planes comprising wire frames connected to the body stick and fabric attached to said wire frames, said front plane being curved to present a concave surface upwardly, and the rear plane being curved to present a convex surface upwardly.

In testimony whereof I affix my signature.

FREDERICK C. MORTON.
